UNITED STATES PATENT OFFICE.

CHARLES W. FISCHER, OF SPARKS, NEBRASKA.

TOBACCO-PIPE STEM.

Application filed December 17, 1924. Serial No. 756,593.

To all whom it may concern:

Be it known that I, CHARLES W. FISCHER, a citizen of the United States, residing at Sparks, in the county of Cherry and State 5 of Nebraska, have invented certain new and useful Improvements in Tobacco-Pipe Stems, of which the following is a specification.

This invention relates to a tobacco pipe 10 stem, and particularly to a construction embodying a cooling chamber for the smoke and means to prevent the entrance of material from the pipe bowl into said chamber or the admittance thereto of liquid from 15 the mouthpiece.

In pipes of this character difficulty has been experienced in providing a simple construction adapted to be readily separated for cleaning purposes and which would effectively prevent the entrance to the cooling 20 chamber of tobacco slugs or other material from the bowl of the pipe and also to check the flow of saliva from the mouthpiece into this chamber.

25 Furthermore in the use of different characters of tobacco a modification of the draft of the pipe is often desirable, as with a free burning dry tobacco less draft is required than if the tobacco is of a moist or slow 30 burning character. To obviate the objection stated I have provided a construction in which the cooling chamber and screen attached to the pipe neck or stem are separately or jointly detachable and this chamber 35 provided at its opposite end with a mouthpiece having an inwardly closing check valve the movement of which is regulated to determine the draft of the pipe.

40 The invention has for an object to provide a novel and improved construction of pipe stem comprising a screen member attachable to the pipe bowl and adapted to receive a cooling chamber which is provided at its opposite end with an inwardly closing 45 check valve.

Another object of the invention is to provide an improved construction of the screening cap which is threaded upon the bowl and has threaded thereon the cooling chamber 50 which comprises an elongated member provided at its opposite end with a mouthpiece.

55 Another object of the invention is to provide a novel type of pipe stem comprising a cooling chamber having a valve casing in which a check valve is disposed and an adjustable tip mounted to limit the opening

travel of said valve whereby the draft of the pipe may be regulated.

Other and further objects and advantages of the invention will be hereinafter set 60 forth and the novel features thereof defined by the appended claims.

In the drawing:—

Figure 1 is a longitudinal section through a pipe with the invention applied thereto; 65

Figure 2 is an enlarged vertical section of the mouthpiece;

Figure 3 is a section on line 3—3 of Figure 2; and

Figure 4 is a detail sectional perspective 70 of the screening cap.

Like reference characters designate corresponding parts throughout the several figures of the drawing.

The pipe bowl 10 may be formed of any 75 desired material or configuration and the neck or stem 11 extending therefrom is exteriorly threaded at its end 12. This neck is provided with a conical or tapering aperture 13 communicating with the bowl and which owing to its configuration permits the introduction of a match stem or other device for the purpose of removing any crust or adhering matter which may pass from the bowl. The neck of the pipe is preferably 80 formed of short length so that it will be heated by the tobacco burning in the bowl to an extent sufficient to absorb any moisture and form a crust therein which can be readily removed when the pipe stem is 85 detached.

Mounted upon the neck 11 is a screening cap 14 preferably formed of metal and pressed into a threaded portion 15 which extends from the rim 16 to the head 17 thereof. This head is provided at its upper portion or sector with any desired number of apertures 18 to permit the draft for the pipe, while the lower portion of the head being closed effectually prevents the passage 95 of any particles of tobacco or ash through such apertures. The threaded portion 15 is engaged with the neck of the pipe and the head 19 of the cooling chamber 20 is threaded upon this portion 15 and abuts against the rim 16 as shown in Figure 1. The cooling chamber may be of any desired configuration and is preferably elongated and of enlarged diameter to provide a maximum 100 surface area for cooling the smoke passing therethrough.

The free end of the cooling chamber is

provided with an interiorly threaded socket 21 adapted to receive a valve casing 22 which is formed with a port 23 adapted to cooperate with a check valve 24, for instance of the ball construction shown in Figure 2. This check valve normally closes the valve port to prevent the entrance of moisture or saliva into the cooling chamber, but in the use of the pipe the draft therethrough causes 10 the ball to be rolled away from said port. For the purpose of regulating this draft relative to the character or condition of the tobacco used a tip or mouthpiece 25 is provided and its shank 26 exteriorly threaded 15 into an aperture of the valve casing 22. The passage 27 through this tip member communicates with a groove 28 at the inner end thereof so that when the check valve is in open position the passage through the tip 20 will not be closed.

When it is desired to provide for a minimum draft through the pipe such as in the use of a dry tobacco, this tip may be adjusted inward to the position shown in Figure 25 1 where the ball valve has only a limited movement permitting passage of air through a portion of the port 23 while if a greater draft is required, for instance with moist tobacco, the ball is permitted to completely 30 leave this port, opening the same to its full capacity as shown in Figure 2.

In the application of the invention it will be seen that the cooling chamber may be removed independently of the screening cap 35 if desired for cleaning purposes while these parts may be jointly removed by grasping the flange upon said cap in order to permit access to the neck of the pipe. At the mouthpiece end of the stem the tip is adapted 40 for removal so that access can be readily secured to the valve and its casing for cleansing the same and this tip inserted to the desired extent to effect the regulation of the draft found most desirable with the character or condition of the tobacco used.

This construction provides means by which the passage of any material from the pipe bowl is prevented by the screening cap and

the smoke passing through the open portion of such cap is cooled within the chamber 50 while the chamber is effectually closed against the admittance of moisture or saliva by the seating of the valve at the mouth piece. This improved stem eliminates the usual long narrow draft opening there-through which becomes often clogged, and provides for a free and clean draft under continued use of the pipe which consequently requires less frequent cleaning.

While the specific details of construction 60 have been herein shown and described, the invention is not confined thereto as changes and alterations may be made without departing from the spirit thereof as defined by the appended claims.

Having thus described my invention, what I claim as new and desire to secure by Letters Patent is:

1. A pipe stem comprising a screen member attachable to a pipe bowl, a cooling chamber mounted thereon, a mouthpiece for said chamber provided with a valve seat, a freely movable ball valve disposed thereon, and adjustable means for regulating the opening movement of said valve.

2. A pipe stem comprising a screening cap threaded upon the neck of a pipe bowl, an elongated cooling chamber separately threaded upon the exterior of said cap, a mouthpiece carried by the free end of said cooling chamber and provided with a valve seat, a free ball valve cooperating with said seat, and means mounted in said valve casing and adjustable relative to the seat to limit the opening travel of said valve.

3. In a pipe stem, a cooling chamber mounted upon a pipe bowl and provided with a threaded socket at its free end, a valve casing mounted in said socket and provided with a port, a ball valve adapted to close said port, and an apertured tip mounted in said casing and adjustable to limit the opening movement of said valve.

In testimony whereof I affix my signature.

CHARLES W. FISCHER.
